UNITED STATES PATENT OFFICE.

FREDERICK KOENIGKRAMER, OF CINCINNATI, OHIO, ASSIGNOR OF ONE-HALF TO FRANK KOENIGKRAMER, OF SAME PLACE.

HYDRAULIC CHAIR.

SPECIFICATION forming part of Letters Patent No. 629,037, dated July 18, 1899.

Application filed November 7, 1898. Serial No. 695,661. (No model.)

To all whom it may concern:

Be it known that I, FREDERICK KOENIGKRAMER, residing at Cincinnati, in the county of Hamilton and State of Ohio, have invented 5 certain new and useful Improvements in Hydraulic Chairs, of which the following is a specification.

My invention relates to what are known as "hydraulic chairs," which are adapted to be 10 raised and lowered, reclined, and revolved.

The object of my invention is to provide simple and convenient mechanism for producing these functions so combined as to be operated by means of a single hand-lever. 15 It also forms a useful elevating device.

The features of my invention are more fully set forth in the description of the accompanying drawings, making a part of this specification, in which—

20 Figure 1 is a perspective view of a hydraulic chair. Fig. 2 is a central vertical section through the operating mechanism. Fig. 3 is a central vertical section at right angles to Fig. 2. Fig. 4 is a top plan view of 25 the operating mechanism with the chair removed. Fig. 5 is a bottom plan view of the cylinder-head. Fig. 6 is a perspective view of the upper face of the plunger-head. Figs. 7 and 8 are perspective views of the two-part 30 crank-sleeve.

A represents the pedestal, and B the chair, provided with the usual seat 1, apron 2, and back 3. The apron is hinged to the sliding rod C by means of a link-lever or other suitable means, and the apron is hinged by means 35 of the chair-arms to the reclining back, which in turn is hinged to the seat. When the sliding rod is unlocked, the movable chair parts or any of them are grasped by the operator and the chair reclined to any desired 40 position, the sliding rod sliding longitudinally in the bearings in the wall of the movable cylinder to allow this reclining movement. The pedestal is provided with a stationary cylinder D, which supports the following mechanisms:

E represents a movable cylinder which contains the oil P. The upper part of this cylinder forms a housing F, in which the operating mechanism is mounted, and the chair 45

is supported upon the flange G of this cylinder. Within this housing are journaled the sliding rod C and a friction-plate a, preferably of yoke form, pivoted at one end to a rod b', supported by the housing. The other 55 end is supported by the spring a', so as to be forced normally upward against the sliding rod to normally lock the chair in any desired reclining position. Within this housing is journaled an operating-lever H, provided with 60 a two-part sleeve I J, to be later described. Upon the sleeve I is formed a cam-lug b, which is brought by the rotation of the hand-lever into engagement with a lug b" on friction-plate a to deflect the same and allow the 65 chair to be adjusted to any desired reclined position. The lug on the yoke could be dispensed with; but it allows the slightest possible movement of the lever when the lugs are engaged to release the slide-rod so the 70 chair can be reclined. So, also, in the movement of the lever from one side to the other the deflection of the plate is practically instantaneous, and the slide-rod is not disturbed, except when the lever is expressly held 75 in position to deflect the yoke. The sleeve-section I is secured by set-screws to the operating-lever, and the sleeve part J is loosely journaled on said lever. The fixed sleeve is provided with the shoulders c c' and the loose 80 sleeve with shoulders d d'. The shoulders c engage the shoulders d at the opposite movements of the operating-lever to operate the loose sleeve J and the mechanism connected therewith. This loose sleeve J is provided 85 with lever-arms e e, between which is pivoted a connecting-rod K, which is connected to a piston-rod K', which passes through the head L of the movable cylinder and is provided with a piston-head M. Valves f g are seated, 90 respectively, in said cylinder-head and piston-head and adapted to pass the fluid medium in a downward direction only. From this cylinder-head depends a pin h, cut away at its lower end i. A slot i' is also cut in the 95 piston-rod K'. The purpose of these cuts in the pin and piston-rod is to escape the oil from the stationary cylinder into the movable cylinder, as will be described in the mode of operation. From the bottom of the movable- 100

cylinder head is depended a lock-plate N, pivoted thereto in such a way as to admit of a slight lateral movement beyond the periphery of the movable-cylinder head. Upon the up- 5 per face of the piston-head is a flange O, provided with a slight bevel adapted to engage the inside of the locking plate or lug N to throw said lug out against the inner wall of the stationary cylinder when the piston-head 10 is fully retracted, and so lock the chair against rotary movement.

k represents a coil-spring, one end of which is wrapped around and secured to the sleeve J and the other end is attached to the housing. This spring strains the piston-rod normally upward and retracts the same to its upward position during the pumping operation.

Mode of operation: The oil or other fluid medium is placed, primarily, in the movable cylinder E, which constitutes the oil-reservoir, and it works its way down into the stationary cylinder and between the parts through valves f g. When the operating-lever is rocked in one direction, the fixed sleeve I is rotated until the shoulder c strikes the shoulder d of the loose sleeve. Further movement of the lever in the same direction then moves the two-part sleeve together to reciprocate the piston-rod K'. In practice the pumping 20 stroke is short, say, three-quarters of an inch. The first movement of the pumping-lever from the center downward presses the piston-head downward upon the oil contained in the stationary cylinder and raises the movable cylinder and supported chair, the oil meanwhile passing through the valve f into the space formed in the stationary cylinder, between the movable-cylinder head and piston. The spring k then exerts pressure in an upward direction and retracts the piston-rod. 25 As this rod is raised, the oil passes from the space between the cylinder-head and piston through valve g into the stationary cylinder. It will be seen that the downward stroke of the operating-lever forces the piston-head upon the oil in the stationary cylinder, which, being non-compressible, forces the movable cylinder upward the length of the pumping stroke. The piston-head bearing upon the 30 oil in the stationary cylinder forms a fulcrum to allow of this upward movement. When the piston-head is retracted, more oil flows into the stationary cylinder through the valve g, and upon the next downward stroke of the lever the movable cylinder is raised another pump-stroke length, and so on, the piston and cylinder-head maintaining the same relative positions in their vertical travel in said stationary cylinder. In order to lower 35 the chair, it is necessary to return the oil from the stationary cylinder back into the reservoir or movable cylinder, which I accomplish by means of the following instrumentalities: If the pumping-lever is moved downward a distance farther than the length of the pumping-stroke, it will raise the mov-

able cylinder a proportionate distance, and thus lift the pin h, supported by the movable cylinder-head, from its engagement through the piston-head until the cut i is adjacent to the orifice in the piston-head, thus affording a passage for the oil to escape back through the piston-head to the position between the piston and cylinder-head, and at the same time this lifting of the cylinder beyond the length of the pumping stroke will bring the cylinder-head adjacent to the cut i' in the piston-rod K', allowing the oil to pass between the orifice in the cylinder-head through which the piston-rod passes and the 70 cut or groove in said rod. Thus this final movement of the pumping-lever opens a passage from the stationary cylinder through the piston-head and movable-cylinder head into the reservoir, and the weight of the chair 75 forces the oil through said passage and so allows the chair to be lowered. The distance between the lower termination of the cut i' and the face of the cylinder-head and the distance between the upper termination of the 80 cut i and the upper face of the piston-head should be practically the same, for they determine the length of the pumping stroke, for the reason that the least lifting of the movable cylinder beyond these points opens the 85 passage for returning the oil to the reservoir. It will be seen that the movable cylinder and its supported chair are also revoluble in the stationary cylinder, the bearing of the piston-head on the oil in the stationary cylinder forming the vertical support or journal, and also that the chair may be revolved at any stage of its vertical travel. For the purpose of illustration say the chair has just been raised to the desired vertical position. It is then 90 revolved to its desired adjustment, the lever is then thrown in the reverse direction to its extreme movement or until the clutch-shoulder c' has moved far enough in the reverse direction to engage the shoulder d' of the loose 95 sleeve, which retracts to its utmost the piston-head, bringing the bevel on the flange O into engagement with the pivoted lock-plate N on the bottom of the movable-cylinder head, swinging it laterally beyond the periphery of 100 the cylinder-head sufficient to clamp the movable cylinder to the stationary cylinder. 105

It is very frequently desired to revolve the chair to different positions, and to facilitate this operation I provide the following instrumentalities: On the piston-rod I provide a lug l, adapted to be engaged by the lug b on the fixed sleeve. The lug b is preferably placed in such relation to its sleeve that a slight movement from the locking position of the lever last described toward the center will engage the lug l, raising the chair just sufficiently to disengage the lock-plate N, and thus allow the chair to be revolved. Lug b is placed in such relation to the lever that it 115 will engage lug b' on the yoke-plate at about the central position of the lever. When the 120

chair is locked against revolution, the lever will occupy a position to the extreme right of the position shown in Fig. 2. A slight movement toward the center will first engage lug 5 b with lug l, releasing the locking-plates O N and allowing the chair to be revolved. A little further movement in the same direction will engage lugs b and b'', allowing the chair to be reclined. If this lug l were not employed, it 10 would simply necessitate the swinging of the lever its full movement back to the pumping position in order to unlock the plate N—that is, the fixed sleeve would have to be revolved until the shoulder c would strike the shoulder 15 d, as in the pumping operation, which would release the lock. The parts are preferably so arranged that the lug b will engage the lug b'' on the friction-plate a at the central position of the lever movement, releasing the sliding 20 rod and allowing the chair to be reclined. This arrangement of parts, however, simply relates to the convenience of operation and may be varied so that the relative movements 25 of the chair will be effected otherwise than in the order here described.

The method of raising and lowering the chair in which the piston-head forms the fulcrum and reciprocates between the two cylinder-heads I believe is novel with me. 30 If desired, the sleeves may be omitted from the lever, the lever itself eccentrically connected to the piston-rod, a lug formed on the lever adapted to trip the friction-plate, similar to the lug on the fixed sleeve, and the 35 lever will still accomplish the several functions at different points of the movement, whereby the elevating, lowering, and locking devices may be independently actuated, and I do not wish to be limited to the particular form 40 of lever mechanism shown and described in the mode of operation, except where made specific elements of the claims.

I do not broadly claim the particular sliding lock mechanism herein shown, as that is 45 made the subject-matter of a companion application for a patent on simple revolving and reclining chair mechanism filed of an even date herewith, and it is only claimed herein in combination with the other features peculiar 50 to this form of hydraulic chairs.

The mechanisms herein shown and described can be produced cheaper than other forms hitherto used, both on account of their simplicity and the saving of material.

55 The convenience and effectiveness of the operation are manifestly a considerable improvement over older forms.

Having described my invention, I claim—

1. In a hydraulic chair the combination of 60 a pedestal, a stationary cylinder and its head, supported thereon, a movable cylinder, and its head mounted in said stationary cylinder, a chair supported on said movable cylinder, a piston rod and head mounted in said cylinder and adapted to reciprocate between the 65 movable and stationary cylinder heads, lever

mechanism mounted in the upper part of the movable cylinder connected to said piston-rod, and adapted to reciprocate the same, and valve mechanism mounted in said movable- 70 cylinder head and piston-head, substantially as specified.

2. In a hydraulic chair, the combination of a pedestal, a stationary cylinder supported therein, a movable cylinder and its head mounted in the stationary cylinder, a piston head and rod, lever mechanism connected to said rod, the said rod passing through the movable-cylinder head, and valve mechanism located respectively in the piston-head and 80 movable-cylinder head, adapted to pass the medium from the movable to the stationary cylinder during the pumping operation and from the stationary to the movable cylinder for lowering the chair, substantially as speci- 85 fied.

3. In a hydraulic elevator the combination of a stationary cylinder, a movable cylinder mounted therein, heads formed in the bottom of said cylinder, a piston-head supported in 90 said stationary cylinder under the movable-cylinder head, a piston-rod connected to said piston and passing through said movable-cylinder head, valve mechanism mounted in said movable-cylinder and piston heads adapted 95 to pass the medium downward, devices constructed and arranged to return the medium from the stationary to the movable cylinder 100 at one end of the lever movement, and lever mechanism mounted in the movable cylinder adapted to reciprocate the rod whereby the device may be elevated and lowered, substan- 105 tially as specified.

4. In a hydraulic elevator the combination of a movable cylinder and its head, a stationary cylinder and its head supporting said movable cylinder, a piston-head journaled in the stationary cylinder under the movable-cylinder head, a piston-rod passing through 110 said head and connected to said piston, lever mechanism mounted in the movable cylinder connected to the piston-rod and adapted to reciprocate the same, valve mechanism mounted in said piston and movable-cylinder head adapted to transmit the medium downward, 115 and devices constructed and arranged when the movable cylinder is raised beyond a pre-determined interval constituting the pumping stroke, to return the medium from the stationary to the movable cylinder and lower 120 the device, substantially as specified.

5. In a hydraulic chair, the combination of a pedestal, a stationary cylinder supported thereon, a movable cylinder and its head mounted in the stationary cylinder, a piston head and rod located under the movable-cylinder head, a piston-rod connected to said piston-head passing through the cylinder-head, a tripping-lug and locking-plate attached respectively to said piston-head and 130 cylinder-head, and a lever mounted in the movable cylinder connected to the piston-rod

adapted to reciprocate the same to clamp and unclamp the said cylinders, substantially as specified.

6. In a hydraulic chair, the combination of 5 a pedestal, a stationary cylinder supported thereon, a movable cylinder and its head mounted in said stationary cylinder, a piston head and rod located in the stationary cylinder under the movable-cylinder head, a trip-
10 ping-lug and locking-plate attached respectively to the opposing faces of said piston-head and movable-cylinder head, valves mounted in said head, a lever mounted in said movable cylinder adapted to be oscillated, and connections between said piston-rod and lever adapted to be actuated by the oscillation of said lever to reciprocate said rod and to trip said locking mechanism, substantially as specified.
- 15 7. In a hydraulic elevator the combination of a stationary cylinder and head, a movable cylinder and head mounted therein, a piston head and rod located in the stationary cylinder under the movable-cylinder head, valve-
20 mechanisms in said movable-cylinder and piston heads, a lever mounted in the movable cylinder, a loose sleeve mounted thereon and connected to said piston-rod, a fixed sleeve attached to said lever and adapted to engage
25 said loose sleeve at one end of the lever movement to reciprocate said piston-rod, substantially as specified.
8. In a hydraulic elevator the combination of a stationary cylinder and head, a movable cylinder and head mounted therein, a piston head and rod located in the stationary cylinder under the movable-cylinder head, valve-
30 mechanisms in said piston and movable-cylinder heads, adapted to pass the medium downward, a lever mounted in the movable cylinder, a spring-controlled loose sleeve mounted thereon, and connected to said piston-rod, a sleeve affixed to said lever, adapted to engage
35 said loose sleeve at one end of the lever movement, and devices constructed and arranged to return the medium from the stationary to the movable cylinder at one end of the lever movement, substantially as specified.
- 40 9. In a hydraulic chair the combination of a stationary cylinder and head, a movable cylinder and head mounted therein, a piston head and rod located in the stationary cylinder under the movable cylinder, valves mounted in said heads, locking and trip mechanisms at-
45 tached to the opposing faces of said piston and movable-cylinder heads, a lever mounted in the movable cylinder, a loose sleeve mounted on said lever and connected to said piston-rod, a fixed sleeve attached to said lever and
50 60 adapted to engage said loose sleeve at opposite ends of the lever movement, whereby the

piston-rod may be reciprocated and the locking devices actuated at one of the end movements of said lever, substantially as specified.

10. In a hydraulic elevator in combination with mechanisms adapted to lock the movable portion of the device in a reclined and revolved position, elevating mechanism consisting of a stationary cylinder and head, a movable cylinder and head located therein, a piston head and rod located in the stationary cylinder, valves mounted in the movable-cylinder head and piston-head adapted to pass the medium downward, devices adapted to transmit the medium upward at one of the end movements of the piston-rod, an oscillating lever mounted in the movable cylinder, a loose sleeve mounted thereon and connected to said piston-rod, a sleeve affixed to said lever, and clutches formed on said sleeves adapted to interlock at opposite ends of the lever movement, whereby the elevating mechanism and the locking devices are actuated independently at different points of said lever movement, substantially as specified. 85

11. In a hydraulic elevator the combination of a stationary cylinder, a movable cylinder located therein, a piston head and rod located in the stationary cylinder under the movable cylinder, an oscillating lever mounted in said movable cylinder, a loose sleeve mounted thereon and connected to said piston-rod, a sleeve affixed to said lever, and clutches formed on said sleeves adapted to engage at opposite ends of said lever movement, substantially as specified. 90

12. In a hydraulic elevator the combination of a movable and stationary cylinder and heads, the movable cylinder mounted in the stationary cylinder, a piston head and rod located between the cylinder-heads, valves, devices for locking the reclining and revolving mechanisms, a lever mounted in said movable cylinder, a spring-controlled loose sleeve mounted thereon and connected to said piston-rod, a sleeve affixed to said lever, a lug formed thereon adapted to engage the mechanism for locking the device against inclination, clutches formed on said sleeves adapted to engage at different points of the lever movement, and a tripping-shoulder formed on said piston-rod adapted to be engaged by the tripping-lug on the fixed sleeve, whereby the piston-rod, locking and tripping devices may be independently actuated by the operation of a single lever, substantially as specified. 105

In testimony whereof I have hereunto set my hand.

FREDERICK KOENIGKRAMER.
